Primary Examiner — Marissa J. Cash*Assistant Examiner* — Nicholas J Buffa(74) *Attorney, Agent, or Firm* — LANWAY IPR SERVICES; Chun-Ming Shih(57) **CLAIM**

The ornamental design for an electronic cigarette assembly as shown and described.

DESCRIPTION

FIG. 1 is a top, front and right side perspective view of an electronic cigarette assembly showing my new design;

FIG. 2 is a bottom, rear and left side perspective view of the electronic cigarette assembly;

FIG. 3 is a top perspective view of an electronic cigarette assembly;

FIG. 4 is a front elevational view thereof;

FIG. 5 is a rear elevational view thereof;

FIG. 6 is a left side view thereof;

FIG. 7 is a right side view thereof;

FIG. 8 is a top plan view of thereof;

FIG. 9 is a bottom plan view thereof; and,

FIG. 10 is a top, front and right side exploded perspective view of the electronic cigarette assembly.

The broken lines in the drawings illustrate portions of the electronic cigarette assembly which form no part of the claimed design.
